UNITED STATES PATENT OFFICE.

CHARLES P. SHAW, OF DETROIT, MICHIGAN.

BLANKING DIE AND METHOD OF MAKING THE SAME.

Application filed October 6, 1926. Serial No. 139,878.

This invention relates to dies and has to do more particularly with dies for blanking out shapes from sheet material, and the method of making the dies.

5 Heretofore punches and dies have been made separately out of hard die steel. This practice is expensive, owing to the fact that both the punch and the die must be machined with great care, which involves considerable 10 time and labor and, moreover, due to the fact that the punch and the die are made separately, errors are frequently made, resulting in an imperfect fit between the two members. When this occurs, the imperfect 15 member, or both members, cannot be used, and new members must be made at an additional loss of time and labor.

The present invention aims to provide blanking dies, and a method of making such 20 dies, so as to overcome these objections. According to the invention the punch and the die are made simultaneously, so that one operation forms both members thus insuring that the members are perfect with respect to 25 each other. Both the punch and the die are made from relatively soft metal, as compared with the die steel heretofore used, and a cutting edge is used in conjunction with the relatively soft metal. This cutting edge 30 may be in the form of a hard steel rule placed around the edges of the die so as to co-operate with the punch. The use of the relatively soft metal is advantageous in that the metal may be peened over to correct an inaccurate placement of the cutting rule.

35 The invention will be better understood by reference to the accompanying drawings wherein:

Fig. 1 is a plan view of a piece of metal 40 showing how the punch is cut out from the metal.

Fig. 2 shows the metal which remains after the punch is removed, which is to be used as the die, the die being severed approximately centrally in this view.

Fig. 3 is a view of one of the die halves taken on line 3—3 of Fig. 2.

Fig. 4 is a view similar to Fig. 3 showing the cutting rule placed around the edges of the die.

Fig. 5 is a plan view of the die after the cutting rule has been placed, and the two halves placed together in their original position.

Fig. 6 is an enlarged detail showing the manner in which the metal is peened over to accurately position the rule.

Fig. 7 is a sectional view taken through the punch and die showing how the die is filled in with material after the punch is removed.

The invention can probably be best described by considering the manner in which a die and punch are made. In Fig. 1 a piece of metal of a desired material, such as steel, is shown at 1. The desired design is cut out of this piece of metal by means of a saw or a routing machine. For this purpose holes 2 are drilled through the metal so as to afford starting places for the saw. In this manner, square corners as shown at 3, may be obtained. The use of such holes to provide several starting places for the saw is necessary with such a design as is shown, although in many cases the design will be such that only one starting place will need to be provided, and the complete operation of sawing out the design may be made without again starting the saw.

After the design has been cut out of the metal, the cut out part 5 is removed, and this is to be used as a punch. The remaining metal is to be used as a die and, since the metal is relatively soft, a cutting rule is to be used.

For the purpose of placing the cutting rule in the die, the die may be severed in two, as shown in Fig. 2, thus forming two sections 6 and 7. A cutting rule 8 is placed around the edges of the members 6 and 7 formed by the cut out. This rule is bent to conform with the outlines of the die, and can be so bent while it is relatively soft. After the rule is bent and the die is otherwise completed, the rule may be hardened. The operation of hardening the rule is relatively short, due to the fact that the rule is not of thick material, and the hardening operation does not harden the members 6 and 7 materially because of their large volume of metal.

This rule is preferably of a thickness which is substantially the same as kerf formed by the cutting tool or saw, and thus an accurate fit as between the cutting rule and the punch is obtained. After the rule is shaped, the two members 6 and 7 are brought together and secured, as shown in Fig. 5, and a work-

able material such as soft metal or wood is placed within the rule as shown at 10 (Fig. 7) to hold it in place. This soft metal need not be so thick as the members 6 and 7.

5. The members are now ready to be used as a punch and die. The punch 5 can be secured to a suitable supporting base or structure (not shown), and the die formed by the members 6 and 7 and the rule can also be 10 bolted or otherwise secured to a support or base (not shown). For this purpose the holes 2 which are drilled in the metal 1 may be used for bolts. In the use of a device, as indicated in Fig. 7, a suitable stripper may 15 be provided for stripping the blanked out form from inside the cutting rule. This stripper may be in the form of a spring pressed metallic plate or in the form of a compressible rubber layer, both of which are 20 well known in the art.

In case of inaccuracies in the position of the rule, the relatively soft metal of the members 6 and 7 can be peened over, as shown at 11 in Fig. 6, so as to correct an inaccurate 25 position of the rule. Likewise, should it be necessary to correct the punch, the metal of the punch may be peened over, as shown at 12.

In making a punch and die by the use of a 30 number of starting holes as shown in Fig. 1, it is desirable that these holes be removed from the edge of either member so that the metal is not materially weakened adjacent the edge. Such holes are not used for bolts, 35 or all of the holes, if desired, can be filled in with the soft metal or wood, and the kerf between these holes and the design may be filled in with rule. While it is perhaps preferable and advantageous to divide the die into two 40 parts, as shown in Fig. 2, for the purpose of expediting the placing of the rule, this is not necessary, especially where the die is not of irregular configuration. In some cases it may be desirable to finish the sides of the saw kerf. 45 This would make the finished kerf somewhat wider, and the rule which is to be used is substantially as thick as the width of the finished saw kerf.

I claim:

50. 1. A blanking die comprising a punch and a die which are formed by one operation of cutting the shape to be blanked from a single piece of metal, and a cutting rule fitted around the edges of the die.
55. 2. A blanking die comprising a punch and a die which are formed by cutting the shape to be blanked from a single piece of metal, and a cutting rule fitted around the edges of the die, said rule being of a thickness substantially equal to the kerf formed by the cutting tool.
60. 3. A blanking die comprising a punch and a die which are formed by cutting the shape to be blanked from a single piece of metal, and a cutting rule fitted around the edges of

the die, said rule being of a thickness substantially equal to the kerf formed by the cutting tool, and of a width which is greater than the thickness of the metal.

4. A blanking die comprising a punch and 70 a die which are formed simultaneously by cutting the shape to be blanked from a single piece of metal, a cutting rule fitted around the edges of the die, said rule being of a thickness substantially equal to the kerf formed 75 by the cutting tool, and of a width which is greater than the thickness of the metal, and a filler for holding the rule in place.

5. A blanking die comprising a punch and 80 a die which are formed simultaneously by cutting the shape to be blanked from a single piece of metal, a cutting rule fitted around the edges of the die, said rule being of a thickness substantially equal to the kerf formed 85 by the cutting tool, and a filler for holding the rule in place.

6. A blanking die comprising a punch and 90 a die which are formed by cutting the shape to be blanked from a single piece of metal, and a cutting rule fitted around the edges of 95 the die, the metal of the die being peened over to correct the position of the rule.

7. The method of making blanking dies which comprises, cutting the shape to be blanked from a piece of metal, removing the 100 cut out piece, placing a cutting rule around the edges of the aperture left by the removal of the cut out piece, and using the cut out piece and the remaining metal as a punch and a die respectively.

8. The method of making blanking dies which comprises, cutting the shape to be blanked from a piece of metal, removing the 105 cut out piece, placing a cutting rule of a thickness substantially equal to the kerf formed by the cutting tool around the edges of the aperture left by the removal of the cut out piece, and using the cut out piece and the remaining metal together with the rule as a punch and a die respectively.

9. The method of making blanking dies which comprises, cutting the shape to be blanked from a piece of metal, removing the 110 cut out piece, placing a cutting rule around the edges of the aperture left by the removal of the cut out piece, partially filling in the aperture now bounded by the rule with a workable material, and using the cut out piece and the remaining metal as a punch and a die respectively.

10. The method of making blanking dies which comprises, cutting the shape to be blanked from a piece of metal, removing the 115 cut out piece, placing a cutting rule around the edges of the aperture left by the removal of the cut out piece, partially filling the aperture now bounded by the rule with soft metal, and using the cut out piece and the remaining metal as a punch and a die respectively.

11. The method of making blanking dies 120

which comprises, cutting the shape to be blanked out of a piece of metal, removing the cut out piece, placing a cutting rule around the edges of the aperture left by the removal 5 of the cut out piece, partially filling in the aperture now bounded by the rule, and peening over the metal adjacent the rule to position the same, and using the cut out piece and remaining metal as a punch and a die respectively.

12. The method of making blanking dies which comprises, cutting the shape to be blanked out of a piece of metal, removing the cut out piece, placing a rule in the kerf 15 formed by the cutting tool, positioning the rule by peening over the metal adjacent thereto, and using the cut out piece and the remaining metal as a punch and a die respectively.

13. The method of making blanking dies which comprises, cutting the shape to be blanked out of a piece of metal, removing the cut out piece, severing the remaining metal, fitting a cutting rule around the edge 25 of each severed piece, placing the pieces together and using the cut out piece and the

said two pieces as a punch and a die respectively.

14. The method of making blanking dies which comprises, cutting the shape to be 30 blanked from a piece of metal, removing the cut out piece, and placing a cutting rule around the edges of the aperture left by the removal of the cut out piece.

15. The method of making blanking dies 35 which comprises, cutting the shape to be blanked from a piece of metal, removing the cut out piece, and placing a cutting rule of a thickness substantially equal to the kerf 40 formed by the cutting tool around the edges of the aperture left by the removal of the cut out piece.

16. The method of making blanking dies which comprises, cutting the shape to be blanked from a piece of metal, removing the 45 cut out piece, placing a cutting rule around the edges of the aperture left by the removal of the cut out piece, and partially filling in the aperture now bounded by the rule with a workable material. 50

In testimony whereof I affix my signature.

CHARLES P. SHAW.
